Gregory R. Everman(57) CLAIM

The ornamental design for a golf tee, as shown and described.

DESCRIPTION

FIG. 1 is a top and front perspective view of a golf tee showing my new design;
 FIG. 2 is a front elevational view thereof;
 FIG. 3 is a rear elevational view thereof;
 FIG. 4 is a left side view thereof;
 FIG. 5 is a right side view thereof;
 FIG. 6 is a top plan view thereof;
 FIG. 7 is a bottom plan view thereof; and,
 FIG. 8 is top and front perspective view thereof shown in use condition placed on a surface and with a golf ball placed thereon.
 The broken lines showing a surface and a golf ball are for illustrative purposes only and form no part of the claimed design.
